A. KOKENGE

SIGNALING APPARATUS

Filed April 12, 1924

*Inventor,
Anton Kokenge, by*

G. Kennedy.
Attorney.

UNITED STATES PATENT OFFICE.

ANTON KOKENGE, OF GRANVILLE, IOWA.

SIGNALING APPARATUS.

Application filed April 12, 1924. Serial No. 706,032.

To all whom it may concern:

Be it known that I, ANTON KOKENGE, a citizen of the United States, residing at Granville, in the county of Sioux and State 5 of Iowa, have invented certain new and useful Improvements in Signaling Apparatus, of which the following is a specification.

My invention relates to improvements in 10 signaling apparatus, and the object of my improvement is to supply for the crossing of a highway by a railroad, a signaling device which may be shifted from an unsignaling to a signaling position, and then in succession returned to its unsignaling position, by 15 independent trip mechanisms which are successively actuated by contact of a passing train.

This object I have accomplished by the 20 means which are hereinafter described and claimed, and which are illustrated in the accompanying drawings, it being understood that changes in the precise embodiment of invention herein disclosed can be made within 25 the scope of what is claimed without departing from the spirit of the invention.

In said drawings, Fig. 1 is an elevation of my signaling apparatus as positioned at the intersection of a railroad and a highway, 30 parts being sectioned or broken away, and Fig. 2 is a plan view of parts of the apparatus with other parts removed or broken away.

The numeral 23 denotes one of a pair of 35 ordinary railway rails secured upon the usual cross-ties 24. A base-block 22 of any suitable material is mounted alongside an outer face of one rail 23 and preferably near a highway crossing the railway, so that the 40 stop-sign 1 may be seen at a considerable distance from the highway and from either of opposite directions, as the sign is double-faced.

While the sign 1 is shown as circular, it 45 may be of any other shape, and it is secured diametrically upon a vertical rotatable shaft 3 with its lower end stepped in the base-block 22, the upper end of the shaft being mounted to rotate in a bearing opening in a horizontal terminal of a standard 2, the latter secured rigidly upon the top of a hollow casing support 4 fixed on the base-block. The shaft 3 also traverses a bearing opening in the top of said casing support 50 and carries within the casing around itself

a pin-gear 5 with which is meshed a larger spur-gear 6 on a vertical shaft 7.

On another rotatable vertical shaft 9 in 60 said casing is fixed a relatively small spur-pinion 8 which is in mesh with the gear-wheel 6, and a spring-barrel 12 is fixedly mounted upon the same shaft and incloses a spiral spring 13 whose ends are respectively 65 fixed to the shaft and to the barrel respectively. The upper extremity of the shaft 9 above its orifized bearing in the casing 4 may receive a socketed crank with which 70 the spring may be wound up by rotating the shaft while the said gearing and the shaft 3 are held against rotation by means to be 75 described. A ratchet-wheel 10 is also fixed on the shaft 9 and its teeth are engaged by a pawl 11 pivotally mounted on the casing 4 to prevent retrograde rotation of the shaft 9.

Below the pin-gear 5 the shaft 3 has the 80 oppositely projecting arms 34 of the same shape and length. A pair of like stop members 14 and 33 are fixed on rock-shafts 16 and 31 respectively and relatively positioned to project toward each other to be interposed 85 within the path of rotation of the arms 34 when in their lowered positions. When either member 14 or 33 is swung in a direction or directions indicated by the full lines as to the member 14 and the two pairs of dotted lines as relates to the member 33, they clear the arms 34, but it will be understood that said arms are by means of appropriate setting and independent releasing 90 means swung alternately so that but one is swung out of the path of rotation of the arms 34 at the same time, the other member being then engaged tensionally by the particular arm 34 which is then rotated thereagainst by the propelling action of the driving spring 13. The stop members thus successively limit the scope of rotation in one direction of the shaft 3 and sign 1, so that 95 the sign is alternately positioned in the signaling position shown in Fig. 1 where it may be seen from either direction from the highway, or in a non-signaling position not perceptible from a distance on the highway, that is edgewise to the railway track 100 and parallel with the highway. In its signaling position the sign 1 is held together with the shaft 3 by reason of one arm 34 tensionally engaging with the hither side of the free end of the stop member 33 after a 105

partial rotation of the shaft 3 when the other stop-member 14 is swung upwardly by the signal setting mechanism to be described.

This setting mechanism includes a pressure-member or arm 27 projecting from a short transverse rock-shaft 26 mounted in a bearing 29 abutting upon the outer face of the rail 23, the pressure-member 27 projecting into the path of translatory movement of any suitable and appropriately placed projection on an approaching locomotive or train at a considerable distance from the highway. A tension-spring 28 is connected between said member 27 and a cross-tie 24 to tend to resiliently resist movement of the arm 27 from its normal vertical position indicated by dotted lines toward the right or away from the signaling apparatus. On the rock-shaft 16 which is mounted in a spaced pair of bearings 20 is another and diametrically oppositely projected pair of arms at 17, a coiled tension-spring being connected to the lower arm and tending to rock the shaft 16 to the right. A connecting-rod 19 is connected between the end of the upper arm 17 and a middle part of the setting or pressure member 27. Another coiled tension spring 15 is connected between the outer part of the stop member 14 and the base-block 22 directly below and tending to retain the member 14 in its lowered position.

The signaling apparatus shown may be actuated to set and return the signal 1 in succession, by a locomotive or train approaching the apparatus from either direction along said rails 23, by stationing a setting device such as is shown in the figures on each side of the signal at the proper distance. Such a device (not shown) has its connecting-rod 21, the latter being the like of the other rod 19 but moving reversely for the same functions, connected to the end of the lower rock-arm 17 in the swinging of the shaft 16 and the stop member 14 in the same way.

An approaching train therefore contacts with and swings the pressure member 27 toward the apparatus or signal 1. The connections then swing upwardly the stop member 14 as shown in full lines, releasing the arm 34 which is by the impelling action of the spring 13 rotated toward and into contact with the other stop member 33 which is in its lowered position. The sign 1 is thus rotated from an unsignaling to a signaling position where it remains until rotated to an unsignaling position. The train having moved forward nearly to the highway contacts with the releasing pressure member 32 thus swinging it to the left and swinging up the stop member 33 releasing the arm 34, so that the spring 13 may rotate the shaft 3 a partial rotation to place the sign 1 in a non-signaling position while engaging the

other arm 34 with the further side of the stop member 14, the latter being now in its dotted line lowered position owing to the train having passed away from the pressure member 27 and the reaction of the spring 15. The train in progressing having released the arm 32 it resumes its vertical position by the traction of the spring 35 connected to the base-block.

It will be observed that the action is always positive, and may be constant, as the driving-spring 13 may be re-wound from time to time by a track-walker or inspector.

Having described my invention, what I claim as new, and desire to secure by Letters Patent, is:

1. In a signaling apparatus, a rotatable signaling device, resiliently-controlled means for rotating it in one direction, and independent devices for releasably limiting parts of a rotation of the signaling device, each of said independent devices including a resiliently-controlled operating device.

2. In a signaling apparatus, a rotatable signaling device, means for rotating it in one direction only, and means for releasably limiting the scope of rotation of said signaling device including a movable pressure member, and other elements operatively connected to said pressure member.

3. In a signaling apparatus, a rotatable signaling device, resiliently-controlled mechanism for rotating it in one direction only, said signaling device having a lateral projection, and mechanism for releasably limiting the scope of rotation of said device including a pressure member, a stop element movable into and out of the path of movement of said projection, and operative connections between the pressure member and said stop element.

4. In a signaling apparatus, a rotatable signaling device, resiliently-controlled mechanism for rotating it in one direction only, said device having opposite lateral projections, mechanism for releasably limiting the scope of rotation of said device including a releasable stop therefor movable into and out of the path of movement of said projections, and another releasable stop independently movable into and out of the path of movement of said projections in succession to the first-mentioned stop.

5. In a signaling apparatus, a rotatable signaling device, resiliently-controlled means for rotating it in one direction only, said device having opposite lateral projections, a movable pressure-member, means for resiliently controlling said pressure-member, a resiliently-controlled movable stop member positioned to be moved into and out of the path of movement of said projections, another resiliently-controlled movable stop member also movable into and out of the path of rotation of said projections, another

movable pressure-member, and operative connections between said pressure-members and said stop members respectively, for independent actuation thereof in succession.

5 6. In a signaling apparatus, a rotatable signaling device, means for positively rotating it in one direction, and independent mechanisms including successively operable movable pressure elements and also including stop elements successively moved by said pressure elements to alternately engage and stop the signaling device and release the latter in turn.

10 7. In a signaling apparatus, a rotatable

signaling device, a coiled spring, intermediate operating elements actuated by said spring when wound up under tension, said elements being operatively connected with the signaling device, and independently actuatable mechanisms for alternately stopping and releasing said signaling device including movable pressure elements and acting as an escapement upon the signaling device in releasably limiting its scope of rotation intermittently.

25 Waterloo, Iowa, March 11, 1924.
In testimony whereof I affix my signature.

ANTON KOKENGE.
